UNITED STATES PATENT OFFICE.

TADEUSZ LESZCZYNSKI, OF TOLEDO, OHIO.

TOY WINDMILL.

Application filed March 4, 1922. Serial No. 540,981.

To all whom it may concern:

Be it known that I, TADEUSZ LESZCZYNSKI, a citizen of Poland, residing at Toledo, in the county of Lucas and State of Ohio, have invented certain new and useful Improvements in Toy Windmills, of which the following is a specification.

This invention relates to certain new and useful improvements in toy windmills and embodies a wind wheel driven shaft adapted to drive a reciprocating saw blade with a figure toy pivotally supported upon the frame work of the device and having a link arm connection with opposite ends of the toy.

A further object of the invention resides in the provision of a windmill toy of the type above set forth wherein the blades of the wind wheel are reversibly mounted upon a block or disk fixed to the power shaft to provide for rotation of the power shaft in opposite directions.

With the above general objects in view the invention consists of the novel combination and arrangement of parts hereinafter more fully described in connection with accompanying drawings, and in which like reference characters designate corresponding parts throughout the several views.

In the drawings:

Figure 1 is a side elevational view, partially broken away of the windmill toy constructed in accordance with the present invention showing the wind wheel fixed to the power shaft and the toy figures connected to the saw blade that is driven by the power shaft.

Figure 2 is a horizontal sectional view taken on line II—II of Figure 1 showing the power shaft and the crank arm carried thereby for attachment to the saw blade.

Figure 3 is a vertical sectional view taken on line III—III of Figure 1 showing the link arms of the figure toy pivotally connected to the saw blade.

Figure 4 is a fragmentary side elevational view of the wind wheel showing the rotatable mounting for the wind wheel blade and the adjusting ring for reversing the feathering edges thereof.

Figure 5 is a detail sectional view taken on line V—V of Figure 4 showing one of the guides for the adjusting ring.

Figure 6 is a detail sectional view taken on line VI—VI of Figure 4 showing the 55 rotatable mounting for the wheel blades and the adjusting ring in toothed engagement therewith, and

Figure 7 is a detail sectional view taken on line VII—VII of Figure 4 showing the 60 pinion for adjusting the blade shifting ring.

Referring more in detail to the accompanying drawings, and particularly to Figures 1 and 2, there is illustrated a windmill toy embodying a frame structure including perpendicular posts 1, 2 and 3, the side posts 2 and 3 being connected by brace bars 4, while a base platform section 5 extends between the posts 1 and 2, as clearly shown in Fig. 2. The posts 1 and 2 extend to a greater height than the posts 3 and are connected at their upper ends by brace bars 6. As shown in Figures 1 to 3, a power shaft 7 is journaled in bearing boxes 8 carried by cross braces 9 extending between the posts 2 and 3 adjacent each end of the frame structure.

A pair of figure toys having link arm connection with the opposite ends of a saw blade are connected to the power shaft 7, each toy including a pair of legs 10 rigidly mounted upon one of the upper cross braces 6 as shown in Figure 3, while the legs 10 of the other figure are rigidly mounted upon the base platform section 5. A body portion 11 is pivotally mounted as at 12 between the upper ends of the legs 10 and carries a pair of link arms 13 that are pivotally connected to the opposite ends of a saw blade 14. As shown in Figure 2, the power shaft 7 carries a crank arm 15 that is connected to the link arm of the lower figure and the saw blade 14 as clearly illustrated.

The wind wheel associated with the power shaft 7 is fixed to said power shaft and includes a block or disk 16 of substantial star formation defining alternating peripheral recesses 17 and projections 18. As shown in Figures 4 and 5, an integral arm 19 ex- 95 100

tends outwardly of each recessed portion 17 having the outer face thereof adjacent the outer end of the arm recessed as at 20 with the bottom wall of the recess having a groove 21, the recess being closed by a block 22 retained in position on the arm 19 by fastening devices 23.

An annular band or ring 24 is received in the grooves 21 of the bracket arms 19 for concentric rotation relative to the disk 16 and is retained in position in the arms 19 by the several blocks 22 associated with said arm.

A blade 25 is associated with each disk projection 18, the specific mounting being more clearly shown in Figures 4 and 6, the inner end of each blade carrying a shaft 26 circumferentially toothed as at 27 adjacent the inner end thereof, while the extreme inner end of the shaft 26 is reduced and swivelly mounted as at 28 in a recess 29 formed in the outer end of the projection 18. As shown in Figure 6, one side face of the ring 24 is provided with rack teeth 30 meshing with the teeth 27 upon the shaft 26, shifting movement of the ring 24 relative to said shafts 26 imparting rotary movement to said shafts for reversing the feathering position of the blades 25. The shifting means for the ring 24 includes a bracket 31 mounted in one of the recesses 17 as shown in Figures 4 and 7, said bracket rotatably supporting the shaft 32 that carries a pinion 33 in mesh with ratchet teeth 34 provided upon the inner side of the ring, one end of the shaft 32 carrying a wrench receiving projection to effect rotation thereof. To hold the pinion 33 and ring 24 in adjusted position, a catch pin 35 on the bracket 31 is moved into engagement with said pinion as clearly shown in Figure 7.

From the above detailed description of the device, it is believed that the construction and operation thereof will at once be apparent, it being noted that the wind wheel being operated by wind pressure, the power shaft 7 is rotated thereby and through the medium of the crank arm 15 upon said shaft, the saw blade 14 is reciprocated by the link arm connection 13 between the saw blade and the toy figures creating the impression of said toy figures operating the saw. To reverse the direction of rotation of wind wheel, the spring catch 35 is released from the pin 33 as shown in Figures 4 and 7 and a wrench supplied to the key end of the shaft 32 will rotate said pinion and cause a shifting movement of the ring 24 relative to the shaft 26 of the wind wheel blade 25, the engagement 27-30 between said ring and shaft reversing the feathering position of said blades.

While there is herein shown and described the preferred embodiments of my

invention, it is to be understood that minor changes in the construction, combination and arrangement of parts may be made without departing from the spirit and scope of the invention.

70

Having thus described the invention, what I claim is:—

1. A windmill toy of the class described, comprising a frame, a power shaft journaled therein, a wind wheel fixed to one end of the power shaft, a crank arm carried by the other end thereof, a pair of figure toys supported on said frame, link arms carried by said figure toys, a saw blade connected at its opposite ends to said link arms and to said crank arm, said wind wheel including a disk fixed to said power shaft, radial blades swiveled in said disk, bracket arms carried by said disk and projecting radially therefrom and means engaging said blades and guided by the bracket arm for reversing the feathering positions of said blades.

80

2. A windmill toy of the class described, comprising a frame, a power shaft journaled therein, a wind wheel fixed to one end of the power shaft, a crank arm carried by the other end thereof, a pair of figure toys supported on said frame, link arms carried by said figure toys, a saw blade connected at its opposite end to said link arm and to said crank arm, said wind wheel including a disk fixed to said power shaft, radial blades swiveled in said disks, bracket arms carried by said disks and projecting radially therefrom, a ring adjustably mounted in said bracket arms and a toothed engagement between said ring and blades for reversing the feathering positions of the blade.

95

3. A windmill toy of the class described, comprising a frame, a power shaft journaled therein, a wind wheel fixed to one end of the power shaft, a crank arm carried by the other end thereof, a pair of figure toys supported on said frame, link arms carried by said figure toys, a saw blade connected at its opposite end to said link arm and to said crank arm, said wind wheel including a disk fixed to said power shaft, radial blades swiveled in said disk, bracket arms carried by said disk and projecting radially therefrom, a ring adjustably mounted in said bracket arms, a toothed engagement between said ring and blade, and means for shifting said ring to reverse the feathering positions of the blade.

100

4. A windmill toy of the class described, comprising a frame, a power shaft journaled therein, a wind wheel fixed to one end of the power shaft, a crank arm carried by the other end thereof, a pair of figure toys supported on said frame, link arms carried by said figure toys, a saw blade connected at its opposite end to said link

arm and to said crank arm, said wind wheel including a disk fixed to said power shaft, radial blades swiveled in said disk, bracket arms carried by said disk and projecting 5 radially therefrom, a ring adjustably mounted in said bracket arms, a toothed engagement between said ring and blade, a pinion rotatably supported on said disk, and gear teeth formed on a portion of the inner face of said ring meshing with said pinion to effect shifting movement of said ring.

In testimony whereof I affix my signature.

TADEUSZ LESZCZYNSKI.
